UNITED STATES PATENT OFFICE.

EDWARD K. MORRIS, OF BALTIMORE, MARYLAND.

COLLAPSIBLE BOX.

Application filed February 20, 1923. Serial No. 620,170.

To all whom it may concern:

Be it known that I, EDWARD K. MORRIS, a citizen of the United States, residing at Baltimore city, State of Maryland, have 5 invented certain new and useful Improvements in Collapsible Boxes, of which the following is a specification.

This invention relates to boxes made of paper, paste-board and similar material 10 and constructed so as to be collapsible into small and compact form when not in use, for convenience in shipment and storage.

The invention has for its object to provide a box of the kind stated which is 15 collapsible in a novel and improved manner, and which can be easily unfolded and set up ready for use, and which is also provided with novel and improved means for securely holding it in set-up position.

20 The object stated is attained by means of a combination and arrangement of parts to be hereinafter described and claimed, and in order that the same may be better understood, reference is had to the accompanying drawings, wherein—

Figure 1 is a perspective view of the box set up ready for use;

Fig. 2 is a bottom plan view thereof;

Fig. 3 is a cross-section on the line 3—3 30 of Fig. 2;

Fig. 4 is a perspective view of a fragment of the box showing the same partly collapsed, and

Figs. 5 and 6 are plan views of blanks 35 employed in the construction of the box.

The preferred embodiment of the invention has been disclosed, but it will be understood that various changes and modifications may be made without departure from 40 the spirit and scope of the invention as claimed hereinafter.

Referring specifically to the drawings, the box is shown as hexagonal in shape, but it will be understood that it may be 45 given any other desired shape, and it will be made of paper, paste-board or analogous material.

The reference numeral 10 denotes the bottom of the box, and integral therewith are 50 two diametrically opposite side walls 11 of the box. The box bottom has a transverse median crease, shown by the dotted line 10^a in Fig. 5, so that it may be folded. The side walls 11 will be bent upwardly on the dotted lines 11^a, so as to extend perpendicularly 55 with respect to the box bottom. The walls 11

have end flaps 12 for attachment to the other side walls 13 of the box, and at the junction of said flaps and walls are creases, the same being shown by the dotted lines 60 12^a in Fig. 5. The blank out of which the box bottom 10 and the side walls 11 are fashioned is shown in Fig. 5.

The side walls 13 are arranged in two diametrically opposite pairs, each pair being 65 a single sheet having a transverse crease 13^a along which the sheet is bent to form the two adjacent side walls. Fig. 6 shows this sheet or blank. A similar blank is provided for the other pair of walls 13. 70 In assembling the box, the two blanks forming the side walls 13 are pasted or otherwise permanently secured to the flaps 12, after the walls 11 are bent to extend perpendicularly with respect to the box bottom 75 10, the length of the blanks forming the walls 13 being such that they lap the flaps 12.

At the bottom of each blank forming the walls 13 are flaps 14 and 15 which lap 80 the under side of the box bottom 10 when the box is erected. The flap 14 is on one wall 13 and the flap 15 on the adjacent wall 13. The flap 14 is formed with a tongue 14^a and a crease 14^b, which are for 85 a purpose to be presently described. When the walls 13 are erected, the inner ends of the flaps 14 and 15 overlap for a short distance, and these lapping portions are fastened together by staples or other suitable 90 devices 16. In the box bottom 10 are diametrically opposite slits 17 to receive the tongues 14^a, the latter being inserted into the slits when the side walls 13 are erected, 95 whereby said walls are securely interlocked with the box bottom 10.

The box is collapsible or foldable, but before this can be done it is necessary to withdraw the tongues 14^a from the slits 17 to break the connection between the box bottom and the side walls of the box. The box bottom 10 may now be folded upwardly on the crease 10^a so that its two halves lie flat and closely alongside each other between the folded side walls. As the side walls are free from the box bottom when the tongues 14^a are withdrawn from the slits 17, said walls can be folded, so that 100 three adjacent walls are on one side of the folded bottom, and the other three on the other side of said bottom. The side walls are flexibly connected at the corners of the 110

box by means of the creases 12^a and 13^a, and the folds are made at said creases. The flaps 14 and 15 are also foldable to lie between the folded side walls, the folds being made on the creases 14^b. It will be noted that in collapsing the box the corners where the bottom flaps 14 and 15 overlap will, with the box fully collapsed, in some instances slightly crumple, the paper yielding

10 to permit this flat folding.

The box is provided with a lid or cover 18 which is foldable along a median line 18^a so that it now is flat and may be placed inside the box when the latter is folded as hereinbefore described. It will be understood that the depending sides 18^b of the lid are foldable inwardly to lie flat against the main body portion of the lid.

In order to hold the box securely set-up or unfolded in position for use, a tie device is provided, the same being a tape or string 19. One end of this tie device passes through a pair of vertically spaced perforations 20 in one of the side walls 13, and the other end passes through similar perforations 21 in the diametrically opposite wall 13. Intermediate its ends, the tie device passes across the bottom 10 of the box and through the slits 17. Between the perforations in the walls 13, the tie device is located inside said walls, and as it issues from the bottom perforations it extends across the bottom corner of the box and outside the flaps 14 to the slits 17, between which latter it runs across the inner surface of the box bottom 10. The tie device also extends along the tongues 14^a in the direction of the length thereof. The two ends of the tie device, as they issue from the top perforations of the side walls 13, are carried across the top of the lid 18, and upon drawing said ends together and tying the same together as shown in Fig. 1, the lid is held in place, and the box is held set up ready for use and prevented from collapsing.

The tie device 19 also serves to facilitate the operation of setting up the box, by guiding the tongues 14^a to the slits 17 and inserting the same thereinto. This operation will be best understood from an inspection of Fig. 4 which shows a fragment of the box partly unfolded. When the tie device 19 is drawn tight by pulling on its ends, the folded box bottom 10 is drawn downwardly and unfolded, and at the same time the side walls are spread and properly set up. The movement of the bottom and the side walls of the box, as they unfold as just described, carries the tongues 14^a to the slits 17 and upon reaching the latter, the tongues pass thereinto. This insertion of the tongues into the slits is automatically effected by that portion of the tie device which extends along the tongues and enters the slits, the tightening of the tie de-

vice causing the same to push the tongues through the slits.

I claim:

1. A collapsible box comprising side walls which are flexibly connected at the corners 70 of the box, a bottom which is foldable inwardly between the side walls on a median line, a pair of diametrically opposite side walls having tongues at the bottom and the box bottom having slits into which the 75 tongues are removably insertible, and a tie-string threaded at its ends through opposite side walls and passing intermediate its ends over the bottom corners of the box and across the box bottom, said intermediate portion of the tie-string being also threaded through the slits of the box bottom, said tie string further extending longitudinally over the tongues on the outside thereof whereby to draw said tongues securely into 80 position and prevent their disengagement from the slits.

2. A collapsible box comprising side walls which are flexibly connected at the corners 90 of the box, a bottom which is foldable inwardly between the side walls on a median line, a pair of diametrically opposite side walls having tongues at the bottom and the box bottom having slits into which the 95 tongues are removably insertible, and a tie-string threaded at its ends through opposite side walls and passing intermediate its ends over the bottom corners of the box and across the box bottom, said intermediate portion of the tie-string being also threaded through the slits of the box bottom, and extending 100 along the tongues on the outside thereof whereby to draw said tongues securely into position and prevent their disengagement 105 from the slits.

3. A collapsible box comprising side walls which are flexibly connected at the corners 110 of the box, a bottom which is foldable inwardly between the side walls on a median line, opposite side walls of the box having 115 inwardly and transversely foldable flaps lapping the box bottom on the outside thereof and provided with tongues, the box bottom having slits into which the tongues are removably insertible, and a tie-string threaded at its ends through the aforesaid opposite side walls and passing intermediate its ends over the bottom corners of the box and across the box bottom, said intermediate portion of the tie-string being also threaded through the slits of the box bottom, said tie string further extending longitudinally over the tongues on the outside thereof whereby to draw said tongues securely into position and prevent their disengagement from 120 the slits.

4. A collapsible box comprising side walls which are flexibly connected at the corners 125 of the box, a bottom which is foldable inwardly between the side walls on a median 130

- line, opposite side walls of the box having inwardly and transversely foldable flaps lapping the box bottom on the outside thereof and provided with tongues, the box bottom having slits into which the tongues are removably insertible, and a tie-string threaded at its ends through the aforesaid opposite side walls and passing intermediate its ends over the bottom corners of the box 5 and across the box bottom, said intermediate portion of the tie-string being also threaded through the slits of the box bottom, and extending across the flaps and along the tongues on the outside thereof said tie string 10 further extending longitudinally over the tongues on the outside thereof whereby to draw said tongues securely into position and prevent their disengagement from the slits. 15
5. A collapsible box body formed of three blanks, one of which has a body portion of regular hexagonal form constituting the bottom of the box, said blank having a fold crease extending between opposite angles 20 and being provided on the sides parallel to the fold crease with rectangular side forming portions, the remaining blanks forming a like pair and each having a pair of rectangular side forming portions defined from 25 each other by a fold line, each of said side 30 forming portions being attached to a respective side forming portion of the first blank and provided with a bottom flap foldable under the body of the first blank, the bottom flaps of each of said pair having their adjacent portions overlapping and provided with a fold crease constituting an extension, when the blanks are assembled, of the fold line between the two side forming portions of the 35 respective blank. 40
6. A collapsible box body consisting of a hexagonal bottom portion having a fold crease extending between opposite corners and six side walls foldably connected each to each, two opposite side walls being foldably connected to the edges of the bottom 45 parallel to the crease line and the remaining side walls being free from said bottom and arranged in pairs between the first two side walls, the side walls of each pair each having a bottom flap, the bottom flaps of each pair having their adjacent ends overlapping and connected and one of each pair of bottom flaps being creased to fold with the respective pair of said walls, the end 50 flaps being defined from each other by a slit whereby to permit such overlapping. 55

In testimony whereof I affix my signature.

EDWARD K. MORRIS.
